DRIVING CONNECTION FOR LACE
MAKING MACHINES

Hugo Mehler, Churchville, Pa.

Application June 1, 1935, Serial No. 24,467

5 Claims. (Cl. 96—20)

This invention deals with the art of lacemaking machines, and is concerned particularly with certain driving connections employed in conjunction with the jacquard control which ordinarily 5 is included in a lacemaking machine.

A lacemaking machine of conventional design ordinarily includes a bed in which is operatively mounted a plurality of shafts for controlling braiding operations on the part of the spindles 10 which carry the thread. The controlling functions are effected by longitudinal movement of the shafts across the bed of the machine, and this invention has in view, as its primary object, the provision of driving connections between the 15 jacquard control, and these shafts in the bed, whereby adjacent shafts are rendered simultaneously and yet independently operable.

More particularly, this invention contemplates a driving connection which provides for a depression of a pair of adjacent shafts, which driving connection will, at the same time, permit either shaft to be depressed while the next adjacent shaft is maintained in its normal upraised position.

A detailed object of the invention is to provide in a driving connection of the character noted a member which is carried by arms extending from the shafts to move the shafts together in one direction, but which member is movable relative to either arm so that its respective shaft may be depressed independently of the next adjacent shaft.

These and other more detailed objects and advantages will in part become apparent, and in 35 part be hereinafter stated.

The invention, therefore, comprises a plurality of shafts from which extend arms, said arms being formed with recesses, cross pieces extending across adjacent arms and received in the recesses, and operating links extending from the cross pieces to the jacquard control.

For a full and more complete understanding of the invention, reference may be had to the following description and drawing of the invention, wherein:

Figure 1 is a fragmentary plan view bringing out the disposition of the plurality of shafts and the driving connections therefor,

Figure 2 is a side view partly in section and 50 partly in elevation, and with parts broken away, bringing out the said driving connections, and

Figure 3 is an enlarged detail view bringing out the rocking of the cross pieces.

Referring now to the drawing, wherein like 55 reference characters denote corresponding parts,

I have shown in Figure 1 a plurality of driving shafts 10 which are mounted for reciprocation in the bed of a lacemaking machine, which is designated 11, and shown in Figure 2. These shafts 10 are connected at their upper ends to 5 mechanism controlling the operation of the spindles which carry the thread going into the lace product.

However, this invention is not concerned with that phase of the lacemaking. It is suffice 10 to say that the members 10 are movable vertically with respect to the bed 11. Attention is also called to the fact that these shafts 10 are disposed in two ring-like arrangements, there being an inner ring of the shafts 10, and an outer 15 ring, the shafts in one ring being staggered with respect to the shafts in the other ring.

Referring now to Figure 2, it is noted that each of the shafts 10 is provided with a collar 12 and a coil spring 13 disposed about each of the shafts 20 10, and it is retained between the collar 12 and the bed 11 of the machine. These springs 13 normally maintain the shafts 10 in an upraised position in which abutments, shown at 14, engage the lower face of the bed 11. At their lower 25 ends each of the shafts 10 is provided with a pair of arms designated 15, which are drivably connected to the shafts 10 by the connection comprising hub portions 16 and set screws 17.

Referring particularly to Figure 1, it will be 30 noted that the arms 15 carried by each of the shafts 10 are disposed in an angular relation with respect to one another. At their extremities each of the arms 15 is enlarged to provide a portion having a recess 18, the recesses 18 in adjacent 35 arms together defining what is in effect, a unitary socket.

A cross piece 19 is received in the socket defined by adjacent recesses 18, and connected to the cross piece 19, centrally thereof, is a link 40 20 which at its lower end is connected as indicated at 21 to a bell crank 22 that is mounted on the frame of the machine, which frame is designated 23, and which bell crank is connected to the jacquard control, as indicated at 24. It 45 is noted that the link 20 is connected to the cross piece 19 by a hook member 25 that extends between the extremities of the arms 15, which hook member is anchored in the middle of the cross piece 19.

Referring now particularly to Figure 2, the operation of the above described driving connection may be briefly described as follows. With the parts in the position illustrated, it is evident that either one of the shafts 10 may be lowered, with 55

respect to the bed 11, in which event the arm 15 of the shaft being lowered, is merely withdrawn from the cross piece 19, in which event the latter rocks slightly, but is retained in the socket in the recess 18 of the adjoining cross piece, as indicated in Figure 3.

If both of the shafts 10 are to be lowered against the influence of the springs 13, a pull on the connection 24 will be transmitted through the bell crank 22 to cause the ring 20 to pull the cross piece 19 downwardly, whereupon both of the arms carrying the cross piece 19 will be moved downwardly, and corresponding movement is imparted to the respective shafts 10.

15 However, by this same driving connection being availed of between each of the adjacent arms 15, movement of the latter downwardly will not affect any other of the shafts, it being only the movement of the cross pieces 19 downwardly 20 which has this effect.

While a preferred specific embodiment of the invention is hereinbefore set forth, it is understood that I am not to be limited to the exact mechanisms illustrated and described, as various 25 modifications of these details may be provided in putting the invention into practice, within the purview of the appended claims.

I claim:-

1. In a lacemaking machine, a pair of shafts, 30 arms extending from each of the shafts, said arms having recesses in their extremities, said recesses defining a socket, a cross piece in the socket, and a link connected to said cross piece.

2. In a lacemaking machine, a pair of shafts, 35 arms extending from each of the shafts, said arms having recesses in their extremities, said

recesses defining a socket, a cross piece in the socket, a link connected to said cross piece, and means for operatively connecting the link to a jacquard control.

3. In a lacemaking machine, a bed, a plurality 5 of shafts disposed in said bed for vertical movement with respect thereto, a jacquard control, and driving connections between the jacquard control and the said shafts, said driving connections including two independent connections to 10 each of said shafts, either of which may be rendered effective to move the shaft at the same time rendering the other connection ineffective.

4. In a lacemaking machine, a bed, a plurality 15 of shafts disposed in said bed for vertical movement with respect thereto, a pair of arms carried by each of said shafts, each arm of each shaft extending towards similarly extending arms of adjacent shafts, a jacquard control, and driving connections between the jacquard control 20 and said arms, each driving connection being common to the arms extending from adjacent shafts.

5. In a lacemaking machine, a bed, a plurality 25 of shafts carried by the bed in vertical position and movable with respect thereto, yieldable means normally maintaining said shaft in upraised position with respect to the bed, a pair of arms carried by each of said shafts on the underside of the bed, a jacquard control, and connections between 30 the jacquard control and arms whereby either arm may be constituted an effective connection for moving the shaft to which it is directed downwardly against the influence of the yieldable means. 35

HUGO MEHLER.
